COAT HANGER

William A. Ringler, Wayne, Pa., assignor to The Gardner-Richardson Company, Middletown, Ohio, a corporation of Ohio

Application May 28, 1942, Serial No. 444,819

9 Claims. (Cl. 223—87)

My invention relates to coat hangers and has as the objective the construction of such a hanger from relatively thin paperboard.

My objectives are simplicity in construction, and simplicity in manufacture and setting up, the elimination of metal, and the use of double thickness so that relatively thin board can be used and a strong enough structure result.

At the present time saving of metal is a specific requirement for all manufacturers, and the coat hanger of my invention will have sufficient strength and durability to replace metal coat hangers. Incident to its construction is the provision of a somewhat expanded structure, which will adapt itself to the problem of hanging up garments with the minimum tendency to form creases in them. In producing a handle for the structure so that it can be placed on a hook, I prefer a mode of construction which will accommodate itself to easy manufacturing methods, and as will be noted, I provide four thicknesses of material at the sloping shoulder elements of my device where the strain of the load is applied to the elongated transverse element.

I accomplish my objects by that construction and arrangement of which a specific example will be illustrated and described, the inventive features whereof will be set forth in the claims that follow, to which reference is hereby made.

In the drawing—

Figure 1 is a plan view of the preferred form of blank, as cut and stamped ready for folding.

Figure 2 is a like view of the parts when folded.

Figure 3 is a detail showing the detachment of the handle member prior to setting up the hanger.

Figure 4 is a side elevation of the completed set-up structure.

Figure 5 is a section on the line 5—5 of Fig. 4.

Figure 6 is a plan view of a modified blank.

The elongated blank has a body portion 1, and a handle portion 2, the latter being separated in the cutting out operation so that there are only a few nicks 3 connecting the same to the body portion, thus facilitating tearing off later, while holding the composite blank together during folding and gluing. The main body portion has two outer panels 4 and 5 defined by score lines from the rest of the body portion. A piece is entirely removed at 6 inwardly from most of the panel 4, and a long flap 7 is formed inwardly of the panel 5, shaped to be thrust through the opening at 6. The blank is scored at 8 midway

of its length, which score also passes through the handle portion 2. The branches 9 and 10 at the two ends of the main portion of the blank and which extend around the ends of the cuts at 6 and 7 form the shoulder portions of the hanger, and the two central portions 11 and 12, form the upper part of the hanger, there being a slot 13 in the score line 8 midway of the portions 11 and 12, for reception of the hook.

The branches 9 and 10 are formed with scores 14 and 15, angularly related to each other and converging on the central score 8 to form depressible double triangular portions to impart the slope to the shoulder portions. To facilitate bending the central score reversely at this point, slots 16 may be cut therein in forming the blank. Also, if desired, holes 17 may be punched in the angular scores also for a like purpose.

It is preferred to cut tongues 18 in the flap 7, and notches 19 in the outer edge of the panel 4, to provide an interlock, as will be described.

Referring to the handle portion of the blank, it has the two hook-shaped portions 20 and 21 which match each other and the panels 22 and 23, which form the gripper element of the hook. These gripper elements do not need to be scored in continuation of the scores marking out the panels 4 and 5.

In making up the hanger in the flat, the entire blank may be provided with a line of cement as at 24 in Figure 6 and be folded along the central score 8 to cement the members 4 and 5, and the members 22 and 23 together, thus making a double thickness structure. In such a case the tongues 18 and the notches 19 will not be needed, and the structure will be shipped in the doubled form. Where the tongued construction is used, the structure may be shipped unfolded and entirely set up when put into use.

In either event the handle portion is pulled away from the main body portion (Fig. 3) and in doubled form thrust up through the slot 13 whereupon the hook protrudes and the gripper panels will catch on the unslotted portion of the scored portion 8 (Fig. 4). After thrusting the handle into place, the shoulders are formed by pushing down on the central score line, then at the same time the main body portion is doubled on itself with the flap 7 thrust through the opening 6, and the tongues 18 bent and thrust under the panel 4, in the notches 19 thereof.

The result of this preferred form is to present an inverted V-shaped transverse portion A (Fig. 5) over which trousers may be laid, or a skirt folded and laid, without any sharp edges pre-

sented to the garment as in a simple coat hanger of metal. The shoulder portions will also tend to remain expanded due to the scores defining the two outer panels 4 and 5 permitting bending of the board at that point. The edges of the panels 4 and 5 and of the flap 7, may be scalloped in order to resist sliding of garments hung across the lower portion of the completed hanger.

In the glued type of structure, the flap 7 will protrude so that when thrust into place in the act of inserting a garment over the lower portion of the structure to give a similar inverted triangular effect. The sloping shoulder portions will also tend to expand somewhat, although not so much as in the preferred structure.

When made of .030 kraft with chestnut filler (as an example) the hanger will be very sturdy, and repeated use thereof will be possible. There is double thickness for strength, and four thicknesses at the shoulders. It may be desirable to make the handle portion separately and glue it completely together thus giving somewhat more resistance to bending under careless imposition of weight on the hanger when in use.

Having thus described my invention, what I claim as new and desire to secure by Letters Patent is:

1. A paperboard coat hanger comprising a medially folded blank, a cut-out portion intermediate its length when folded, means for holding the blank in doubled position, and shoulder portions for the blank formed by fold lines converging to the central folding line, whereby the blank may be reversely folded inwardly at the shoulder portions forming four thicknesses of material at the resulting sloping structure, and a handle portion for the hanger formed of a separate piece of paperboard folded double and cut when so folded to form a hook portion and a basal projecting portion, said blank having a slot in its medial fold line for passage of the hook portion but not the basal portion.

2. A paperboard coat hanger comprising a medially folded blank having a cut-out portion intermediate its length when folded, means for holding the blank in doubled position, and shoulder portions for the blank formed by fold lines converging to the central folding line, whereby the blank may be reversely folded inwardly at the shoulder portions forming four thicknesses of material at the resulting sloping structure, and a handle portion for the hanger formed of a separate piece of paperboard configured to form hook portions in opposition and connected by a fold line and basal projecting portions at the ends of the hook portions, said piece of paperboard being folded double whereby said hook portions are connected at their tops, said blank having a slot in its medial fold line for the passage of the hook portions but not the basal portions, and said hook portions being so inserted in said blank whereby the hook portions are held together at their tops by the connection between them and at their basal portions by their engagement with said folded blank.

3. A paperboard coat hanger comprising a medially folded blank having a cut-out portion intermediate its length when folded, means for holding the blank in doubled position, and shoulder portions for the blank formed by fold lines converging to the central folding line, whereby the blank may be reversely folded inwardly at the shoulder portions forming four thicknesses of material at the resulting sloping structure, and a handle portion for the hanger formed of a

separate piece of paperboard configured to form hook portions in opposition and connected by a folded line and basal projecting portions at the ends of the hook portions, said piece of paperboard being folded double whereby said hook portions are connected at their tops, said blank having a slot in its medial fold line for the passage of the hook portions but not the basal portions, and said hook portions being so inserted in said blank whereby the hook portions are held together at their tops by the connection between them and at their basal portions by their engagement with said folded blank, said intermediate cut-out portion being formed in one of the halves of the blank by a flap which when the blank is doubled, is insertable through the cut-out portion in the other one of the halves.

4. A paperboard coat hanger comprising a medially folded blank having a cut-out portion intermediate its length when folded, means for holding the blank in doubled position, and shoulder portions for the blank formed by fold lines converging to the central folding line, whereby the blank may be reversely folded inwardly at the shoulder portions forming four thicknesses of material at the resulting sloping structure, and a handle portion for the hanger formed of a separate piece of paperboard configured to form hook portions in opposition and connected by a fold line and basal projecting portions at the ends of the hook portions, said piece of paperboard being folded double whereby said hook portions are connected at their tops, said blank having a slot in its medial fold line for the passage of the hook portions but not the basal portions, and said hook portions being so inserted in said blank whereby the hook portions are held together at their tops by the connection between them and at their basal portions by their engagement with said folded blank, said intermediate cut-out portion being formed in one of the halves of the blank by a flap which when the blank is doubled, is insertable through the cut-out portion in the other one of the halves, said flap having tongues cut therein, there being notches in the margin of the blank to receive said tongues.

5. A paperboard coat hanger comprising a medially folded blank having a cut-out portion intermediate its length when folded, means for holding the blank in doubled position, and shoulder portions for the blank formed by fold lines converging to the central folding line, whereby the blank may be reversely folded inwardly at the shoulder portions forming four thicknesses of material at the resulting sloping structure, and a handle portion for the hanger formed of a separate piece of paperboard configured to form hook portions in opposition and connected by a fold line and basal projecting portions at the ends of the hook portions, said piece of paperboard being folded double whereby said hook portions are connected at their tops, said blank having a slot in its medial fold line for the passage of the hook portions but not the basal portions, and said hook portions being so inserted in said blank whereby the hook portions are held together at their tops by the connection between them and at their basal portions by their engagement with said folded blank, said intermediate cut-out portion being formed in one of the halves of the blank by a flap which when the blank is doubled, is insertable through the cut-out portion in the other one of the halves, said flap having tongues cut therein, there being notches in the margin of the blank to receive said tongues, said hook

portions adjacent the basal portions of said handle being notched whereby to produce an engagement with said blank effective in preventing accidental displacement of said handle portion with reference to said blank.

6. A blank for a garment hanger comprising an elongated piece of paperboard having a medial score line throughout its length, said blank being divided by a transverse line of weakening into an elongated and generally rectangular body blank for a garment hanger and a handle blank, said blanks being of substantially the same width, said handle blank being configured to provide opposed hook portions top to top and outlying basal portions, said body blank having a slot in its medial score line centrally and of a length to accept said hook portions but not said basal portions, said body blank having lines of score slanting from the side edges thereof to the medial score line so that when said body blank is doubled triangular portions can be depressed giving a sloping configuration to portions of the top edge of the blank.

7. A blank for a garment hanger comprising an elongated piece of paperboard having a medial score line throughout its length, said blank being divided by a transverse line of weakening into an elongated and generally rectangular body blank for a garment hanger and a handle blank, said blanks being of substantially the same width, said handle blank being configured to provide opposed hook portions top to top and outlying basal portions, said body blank having a slot in its medial score line centrally and of a length to accept said hook portions but not said basal portions, said body blank having lines of score slanting from the side edges thereof to the medial score line so that when said body blank is doubled triangular portions can be depressed giving a sloping configuration to portions of the top edge of the blank, said body blank being further characterized by means for holding the two halves thereof together.

8. A blank for a garment hanger comprising an elongated piece of paperboard having a medial

score line throughout its length, said blank being divided by a transverse line of weakening into an elongated and generally rectangular body blank for a garment hanger and a handle blank, said blanks being of substantially the same width, said handle blank being configured to provide opposed hook portions top to top and outlying basal portions, said body blank having a slot in its medial score line centrally and of a length to

5 accept said hook portions but not said basal portions, said body blank having lines of score slanting from the side edges thereof to the medial score line so that when said body blank is doubled triangular portions can be depressed giving a 10 sloping configuration to portions of the top edge of the blank, and an elongated flap formed in one of the halves of said body blank and adapted to be passed through a cut-out in the other half of said body blank to provide a garment hanger 15 having a lower rail.

9. A blank for a garment hanger comprising an elongated piece of paperboard having a medial score line throughout its length, said blank being divided by a transverse line of weakening into an 20 elongated and generally rectangular body blank for a garment hanger and a handle blank, said blanks being of substantially the same width, said handle blank being configured to provide opposed hook portions top to top and outlying basal portions, said body blank having a slot in its medial score line centrally and of a length to accept said hook portions but not said basal portions, said body blank having lines of score 25 slanting from the side edges thereof to the medial score line so that when said body blank is doubled triangular portions can be depressed giving a sloping configuration to portions of the top edge of the blank, said handle blank being so configured adjacent the hook portions thereof as to 30 present notches for engagement with said body blank in such a manner as to prevent displacement of said handle portion with respect to said body blank.
